US0D1014236S

(12) **United States Design Patent** (10) **Patent No.:** **US D1,014,236 S**
(45) **Date of Patent:** **** Feb. 13, 2024**

(54) **CUSHIONING MATERIAL FOR PACKAGING**

(71) Applicant: **DONG GUAN WANG QUAN PAPER CO., LTD**, Dongguan (CN)

(72) Inventor: **Shenghsieh Kuo**, Hsinchu (TW)

(73) Assignee: **DONG GUAN WANG QUAN PAPER CO., LTD**, Dongguan (CN)

(**) Term: **15 Years**

(21) Appl. No.: **29/904,629**

(22) Filed: **Oct. 10, 2023**

(30) **Foreign Application Priority Data**

Sep. 14, 2023 (CN) 202330598170.4

(51) **LOC (14) Cl.** **09-07**

(52) **U.S. Cl.**

USPC **D9/456**

(58) **Field of Classification Search**
